E. C. HEALY

SUPERVISORY MECHANISM

Filed July 28, 1920

UNITED STATES PATENT OFFICE.

ELLIS C. HEALY, OF EAST ORANGE, NEW JERSEY, ASSIGNOR, BY MESNE ASSIGNMENTS, TO DETEX WATCHCLOCK CORPORATION, OF NEW YORK, N. Y., A CORPORATION OF DELAWARE.

SUPERVISORY MECHANISM.

Application filed July 28, 1920. Serial No. 399,491.

To all whom it may concern:

Be it known that I, ELLIS C. HEALY, a citizen of the United States, residing at East Orange, county of Essex, and State of New Jersey, have invented certain new and useful Improvements in Supervisory Mechanism, of which the following is a full, clear, and exact description.

The invention which constitutes the subject-matter of this application has to do with mechanism adapted to be connected to a valve and for controlling the access to a recording key. That is to say, when the valve is in its normal position access may be had to a recording key but if the valve is not in its normal position the key is rendered inaccessible. As these valves (or "stations") are equipped with a key a time imprint may be made on a record dial of a watchman's clock which indicates the time at which the station was visited by the watchman. So long as these imprints are made at the required intervals, as shown by the record dial, it is a sure indication that the valves at these particular times were in normal position. But if the imprint of a certain station is omitted from the record dial it would be an equally sure indication that the key at that station was inaccessible and therefore that valve was not in normal condition. Of course, if it is a part of the watchman's duty to move the valve from its abnormal to its normal position he could then make the imprint. In any event, the device will have served its purpose.

Referring to the drawings:

Figure 1 is a partly sectional view of the upper portion of an indicator post or yard valve equipped with supervisory mechanism, the receptacle thereof being in section.

Fig. 2 is a section, through the receptacle containing supervisory mechanism, taken at right angles to that of Fig. 1.

Fig. 3 is a section taken on the line 3-3 of Fig. 1.

Fig. 4 is an elevation illustrating a complete valve and its equipment.

The supervisory mechanism herein illustrated, described and claimed is particularly designed to be employed in connection with an indicator post or yard valve which controls a sprinkler system located in an adjacent building. The indicator post is

composed of two sections 10 and 11 which are telescopic with each other and are relatively adjustable. The section 10 is fixed upon and supported by the valve 12 which is to be controlled by the device. Superimposed upon the upper section 11 is a cap 13 secured to the section 11 by means of bolts 14. Rotatably mounted within the cap 13 is a target screw 15 which is held from longitudinal movement by means of the lock nut 16 under the cap and the shoulder 16^a mounted above the cap. There is provided a wrench member 17 which projects upwardly from the target screw 15. The lower end of the target screw is provided with a rectangular socket which engages with the upper end portion of the valve stem, which I have designated by the reference numeral 20. The lower end of this valve stem 20 is provided with a socket member 21 which engages with the upper end of a suitably shaped member 22 constituting a part of the valve 12. In screw-threaded engagement with the target screw 15 is a target nut 24. This nut is provided with one or more grooves in the side thereof which engage the lugs or flanges 26 on the casting 11. The nut 24 may be moved longitudinally by turning the target screw, but is prevented from rotating about its axis by the grooves and lugs 26. The target nut has secured thereto a plurality of indicating or target plates, O, O, and S, S adapted to be viewed through the windows, W, W to indicate the condition of the valve. If the valve is fully "open" the targets O, O, are visible whereas if the valve is closed the "shut" targets S, S, are visible.

All of the mechanism specifically described above is of conventional form and no claim is made thereto except as it forms or constitutes a part of the combination with the mechanism described hereinafter.

The target screw is provided with a bearing 27 upon which is pivoted or journaled a rod 28 and 28^a. This rod is preferably constructed of two parts 28 and 28^a screw-threadedly engaged with each other and thereby forming an adjustable rod or link. A lock nut N may be provided for holding the rod sections in adjusted position. The lower end of this rod is provided with a laterally projecting stud 29 which passes through a slot 30 in the casting 11 and also

through a slot 31 in the container 32, which container is securely fastened to the casting 11. This stud passing, as it does, into the interior of the receptacle or container 32 engages with an angle plate B in turn secured to a vertically movable slide member 33. Rotatably or oscillatably mounted adjacent to the upper end of the casing 32 is a rock shaft 34 having secured thereto at one end a cam 35 adapted to be engaged by the slide 33 to operate said rock shaft. The other end of said rock shaft has secured thereto an arm 36 to which a watchman's key, or other suitable manually operable recording device 37, is secured by means of a flexible chain 38. The casing 32 may be provided with a septum P, through which the rock shaft 34 extends, to conceal and protect the main portion of the mechanism.

20 The specific embodiment of the invention above described is designed to operate as follows:

When the valve 12 is in normal position, in the present case fully open, the parts occupy the position indicated in full lines in Figs. 1 and 2. A watchman in making his rounds may then obtain access to the recording key 37, through the door D of the casing 32, to produce a permanent record in his clock or other recorder indicating that that particular valve was normal (open) at that particular time. If however the valve is in abnormal position, in the present case closed or even partially closed, the key is not available to produce a record and this fact will appear on the record dial turned in by the watchman.

The operation by which the key 37 is rendered inaccessible is substantially as follows:

40 A few rotations of the member 17 in the direction to close the valve cause the slide 33 to elevate to such an extent as to cause the arm 36 to assume the position indicated in dotted lines in Fig. 2, when the key is no longer accessible to produce a record. When the arm 36 has reached the last mentioned position the flat face E of the cam 35 is parallel to and in engagement with the plane face E' of the slide 33 and the cam and arm 36 are locked against rotation until the valve is restored to normal condition. Continued rotation of the valve stem toward valve-closed position simply causes the slide 33 to travel idly past the cam 35 so far as further actuation of the latter is concerned. It will be seen that, by virtue of the weight of the arm 36, chain 38 and key 37 the latter will return to the full line position in Fig. 1 when permitted to do so by restoration of the valve to normal position.

In connection with the specific apparatus herein illustrated and above described, it should be noted that, for proper operation of the system, the movement of the

slide 33 should be substantially parallel to that of the stud 29 and its operating members. In order to insure this condition and to facilitate proper assembly of the device the casing 32 is preferably provided with two positioning lugs or pins L, L each engageable in the vertical slot 30 at opposite ends of the same. These pins are so arranged and designed that when inserted in said slot 30 as indicated in Fig. 1, the line of movement of the slide 33 will bear the proper relationship to the operating elements of said slide. The casing 32 may then be firmly secured to the casing section 11 by any suitable means such as screws 100.

What I claim is:

1. In combination, a valve having a stem, a rectilinearly movable element, means for simultaneously operating said stem and element, a cam having a flat portion associated with said element to be engaged and operated thereby on initial movement of said element in a predetermined direction and locked against movement on further movement of said element in the same direction, and a recording device controlled by said cam.

2. In combination, a valve having a stem, a rectilinearly movable element, means for simultaneously operating said stem and element, a cam having a flat portion associated with said element to be engaged and operated thereby on initial movement of said element in a predetermined direction and locked against movement on further movement of said element in the same direction, a rock shaft to which said cam is secured, a manually operable recording device and means secured to said rock shaft for controlling said device.

3. In combination, a valve having a rotatable stem, a rectilinearly slidable element, means for simultaneously rotating said stem and operating said element, a cam engageable and operable by said element, a rock shaft to which said cam is operatively connected, a member operatively connected to said shaft and spaced axially of said shaft from said cam, and a manually operable recording device controlled by said last named member.

4. In combination, a valve having a rotatable stem, a rectilinearly slidable element, means for simultaneously rotating said stem and operating said element, a cam engageable and operable by said element, a rock shaft to which said cam is operatively connected, an arm operatively connected to said shaft and spaced axially of said shaft from said cam, a watchman's key connected to said arm, and means for rendering said key inaccessible when said arm is in a predetermined position.

5. In combination, a valve having a rotatable stem, a rectilinearly movable ele-

- ment, means for simultaneously operating said stem and element, a member mounted for movement about an axis and operable by and upon initial movement of said element in a predetermined direction and locked against movement on further movement of said element in the same direction, and a recording device controlled by said member.
6. In combination, a valve having a rotatable stem, a rectilinearly movable element, means for simultaneously operating said stem and element, a rock shaft, a member mounted on said rock shaft and operable by and upon initial movement of said ele- ment in a predetermined direction and locked against movement on further movement of said element in the same direction, a manually operable recording device, and means secured to said rock shaft for controlling said device.
7. The combination as set forth in claim 5 in which the recording device is a watchman's time clock key.
8. The combination as set forth in claim 6 in which the recording device is a watchman's time clock key.

In testimony whereof I hereto affix my signature.

ELLIS C. HEALY.
